UNITED STATES PATENT OFFICE.

WILLIAM C. THOMAS, OF COLUMBUS, OHIO, ASSIGNOR TO THE JOHN W. BROWN MANUFACTURING COMPANY, OF COLUMBUS, OHIO, A CORPORATION OF OHIO.

VEHICLE HEAD LAMP.

Application filed February 17, 1926. Serial No. 88,889.

This invention relates to improvements in motor vehicle head lamps and is especially directed to the provision of an improved adjustable bulb mounting for use in connection with such lamps, the principle object of the invention being the provision of a bulb mounting by means of which a lamp bulb may be adjusted longitudinally with respect to the principal axis of an associated reflector and, in addition, also adjustable vertically, or in a plane at right angles to said first named axis, with the end in view of permitting of the adjustment of the lamp so as to secure a desired focal relationship between the light source and its accompanying reflector.

With these and other objects in view, as will appear as the description proceeds, the invention consists in the novel features of construction, combinations of elements and arrangements of parts hereinafter to be fully described and pointed out in the appended claims.

In the accompanying drawing:

25 Figure 1 is a vertical longitudinal sectional view taken through the head lamp and illustrating the bulb mounting comprising the present invention therein,

30 Figure 2 is a fragmentary view disclosing the adjusting means from the rear of the lamp,

Figure 3 is a vertical transverse sectional view taken on the plane indicated by the line 3—3 of Figure 1,

35 Figure 4 is a transverse sectional view on the line 4—4 of Figure 1.

Referring more particularly to the drawing, the numeral 1 designates a lamp casing of any desired exterior configuration.

40 Within the casing there is mounted stationarily the usual parabolic reflector 2, having its open front end closed by a lens mounted in connection with the removable lens ring 3 detachably carried by the open front end of the casing.

The reflector is provided with an axial opening 4 in which is mounted a sleeve 5, the opening 4 being of such diameter as to permit of rocking movement of the sleeve 5 therein to a limited extent. The sleeve 5 is provided with the usual bayonet slot for the removable reception of a pin 6 carried by the base of the incandescent lamp 7. Connected with the sleeve 5 is a guard 8 and disposed between the guard 8 and the sleeve

5 is a bracket 9, which terminates rearwardly in a substantially U shaped portion 10. This portion of the bracket is interiorly threaded for the reception of an adjusting screw 11, the shank of which projects 60 through an elongated slot 12 provided in the rear wall 13 of the casing 1, the outer end of the screw being headed as at 14 and of greater diameter than the width of the slot 12. Manifestly, by rotating the screw 65 11 longitudinal movement will be imparted to the bracket 9 and the connected sleeve 5 so as to move the lamp 7 longitudinally with respect to the principal axis of the reflector, there being a coil spring 15 positioned between the U portion 10 of the bracket 9 and the wall 13 for the purpose of retaining the bulb in its adjusted position and preventing undue rotation on the part of the screw 11.

In order to oscillate the sleeve 5 vertically and to thereby adjust the light source to occupy a position either below or above the plane of the principal axis of the reflector the present invention contemplates the provision of such structure comprising a 80 flexible adjusting strip 16. This strip is arranged within the lamp casing and has its lower end fastened or riveted thereto as at 17. Immediately above its point of connection, as at 17, with the lamp casing the strip 85 is bowed to produce an outwardly directed zone 18 and this portion of the strip then terminates in an upwardly directed flattened extremity which presses upon the rear wall of the casing, the extreme upper end being provided with an opening 19 for the accommodation of the screw 11, the diameter of the opening 19 corresponding closely to that of said screw. Swiveled in connection with the bowed portion 18 of the strip is a nut 20 90 threaded to receive a second adjusting screw 21 which, in turn, has the headed end 22 thereof swiveled in connection with the rear wall of the casing. It will be apparent that by rotating the screw 21 the nut 20 may be 95 advanced longitudinally thereof so as to flex or release the bowed portion 18 of the strip 16 and to thereby provide an adjustment for governing the effective length of said strip so as to raise or lower the screw 11 in the 105 slot 12 provided therefor in the rear wall of the casing. By thus varying the effective length of said strip the sleeve 5 may be rocked in a vertical plane so as to oscillate the lamp 7, enabling the filament thereof to 110

be adjusted to any desired focal position in relation to the axis of the reflector 2. The compound adjustment thereby provided enables the bulb to be set with great precision 5 to insure the proper projection of light rays from the lamp as a whole, enabling variations in the length of the beam projected from the lamp to be readily accomplished and to either cause the light beam to extend above or below the horizontal level of 10 the lamp.

What is claimed is:

1. In a vehicle head lamp, a casing, a reflector therein provided with an axial opening, a lamp support adjustably mounted in said opening, an adjusting screw arranged co-axially with respect to said support for moving the latter longitudinally, a strip mounted within said lamp and formed with a bowed resilient portion, the outer end of said strip being engaged with said screw, and means for flexing the bowed portion of said strip to regulate the effective length thereof and to thereby govern the axial relation between said support and said reflector.
2. In a vehicle head lamp, a casing, a reflector mounted within said casing, a bulb support adjustably mounted in an opening provided in said reflector, a bracket carried by said support, an exteriorly actuated screw

engaged with said bracket and arranged in axial alignment with said support to move the latter longitudinally, a strip secured at one end to said casing and formed to include a bowed resilient portion and a free outer portion engaged with said screw, and an exteriorly operated adjusting means for flexing the bowed portion of said strip to regulate its effective length whereby said support may be oscillated vertically with respect to said reflector.

3. In a vehicle head lamp, a casing, a reflector within said casing and provided with an axial opening, a bulb support movable horizontally and vertically with respect to said reflector, an exteriorly actuated screw projecting through a slot provided in said casing and having the inner end thereof threadedly engaged with said support to adjust the latter longitudinally, a strip fixed to said casing and having a bowed portion and an outer free end engaged with said screw, and exteriorly operable adjusting means for flexing the bowed portion of said strip to vary the effective length thereof whereby said screw is vertically adjusted to rock said support relative to the reflector.

In testimony whereof I affix my signature.

WILLIAM C. THOMAS.
